UNITED STATES PATENT OFFICE.

WILLIAM H. COLLIER, OF PAINESVILLE, OHIO.

LATHE-KNIFE-GRINDING MACHINE.

Application filed May 29, 1922. Serial No. 564,452.

To all whom it may concern:

Be it known that I, WILLIAM H. COLLIER, a citizen of the United States, residing at Painesville, in the county of Lake and State 5 of Ohio, have invented certain new and useful Improvements in Lathe-Knife-Grinding Machines, of which the following is a specification.

This invention relates to grinding machines and has special reference to a machine for grinding the knives of veneer lathes.

The object of the invention is to provide an improved construction of veneer knife 15 grinder wherein a grinding wheel is reciprocated transversely of the machine, while rapidly rotating, novel mechanism being employed for traversing the grinding wheel and reversing its movement at each end of 20 the stroke; the invention also having the further objects of feeding the grinding wheel by improved means toward the knife by a step by step movement of novel character, and of providing a constant flow of 25 water to the grinding wheel during the grinding operation.

In the drawings:

Figure 1, is an elevation of one end of the machine.

Figure 2, is a plan view of the machine with certain parts broken out in order that the details may be shown on a proper scale.

Figure 3, is an enlarged detail view, partly in section and showing the carriage of the machine in side elevation.

Figure 4, is a front elevation of the carriage certain other parts being shown associated therewith.

Figure 5, is a plan view of a portion of said carriage.

Figure 6, is a plan view of the carriage the upper part being removed to show the gearing for reversing the movement of the carriage.

Figure 7, is a section on the line 7—7 of Figure 5.

Figure 8, is a perspective view of a certain feed lever and pawl used herewith.

Figure 9, is a detail view of a portion of the clutch shifting mechanism, one of the parts being shown in one position in full lines and in a second position in dotted lines.

Figure 10, is a section on the line 10—10 of Figure 2.

Figure 11, is a section on the line 11—11 of Figure 10.

Figure 12, is a section on the line 12—12 of Figure 10.

Figure 13, is a diagrammatic plan view 60 showing the general arrangement of the machine.

In the embodiment of the machine here shown there is provided a base or bed 10 having transversely extending ways 11 whereon is slidably mounted a carriage 12.

Journalled in bearings 13 on the bed is a main drive shaft 14 provided with the pulley 15. Secured beneath the carriage 12 and forming part thereof is a gear case or housing 16 through which passes the shaft 14.

Splined on the shaft 14 and supported in bearings 17 on the gear case is a sleeve 18. On this sleeve are mounted the bevelled gears 19 and 20, these gears being oppositely arranged and having their hubs extending toward each other and provided on their ends with clutch teeth 21. Splined on the sleeve 18 between the gears 19 and 20 is a clutch member 22 provided on its ends with clutch teeth 23 engageable with the teeth 21 of the gears 19 and 20 in accordance with the position of the clutch 22. These gears 19 and 20 mesh with a gear 24 which is fixed upon a shaft 25 which extends at right angles to the drive shaft 14.

On the end of the shaft 25 is a pinion 26 which meshes with a rack 27 supported beneath the rear way 11. The clutch 22 is provided with a groove 28 to receive the shipper fork 29.

This shipper fork is carried by a shipper rod 30 projecting laterally from the gear case 16 and provided on its projecting end with a head 31. Extending from side to side of the machine is a rod 32 whereon are slidably mounted the reversing collars 33

which are held in adjusted position on the rod by the set screws 34. Extending laterally from the gear case 16 is a lug 35 on which is pivotally mounted a lever 36, the lever being pivoted intermediate its ends to said lug.

The lower end of this lever is bifurcated and straddles the rod 32, thus being adapted to be brought into engagement with the collars 33 by the movement of the carriage across the machine and the upper end of this lever is provided with an arcuate slot 37 which receives a pin 38 projecting from the head 31.

The upper face of the lever 36 is formed to provide angularly disposed surfaces 39. In the carriage 16 is formed a vertical opening or bore 40 wherein slides a plunger 41 carrying on its

lower end a roller 42 engaging the surfaces 39. The upper end of the bore 40 is closed by a cap 43 and between this cap and the plunger 41 is a coiled compression spring 44 which constantly urges the plunger 41 downward.

In the operation of this part of the device let it be supposed that the shaft 14 is rotating and the clutch 22 thrown into engagement with the gear 19. Under these conditions the lever 36 and the head 31 will be in the positions shown in Fig. 4 and the carriage will be moving to the right of that figure. When the lever 36 engages the collar 33 this lever will be turned upon its pivot until the left hand end of the slot 37 engages the pin 38. During this movement of the lever the plunger 41 will be raised against the action of the spring 44 and the roller will pass over the angle between the two surfaces 39. Continued movement of the carriage to the right will then start the shipper rod moving to the right with respect to the carriage and, because of the roller pressing on the left hand angular surface this movement of the shipper rod will be quick and vigorous so that the shipper fork and clutch will be quickly moved to the right and the clutch will thus disengage from the gear 19 and engage with the gear 20 thus changing the direction of movement of the wheel 24 and consequently reversing the movement of the carriage. In order to prevent accidental movement of the head 31 a keeper spring 45 is secured to the gear case 16 and engages the pin 38 as shown. There will naturally be times when it is desirable to stop the carriage and to this end the head 31 is provided with a bevelled notch or groove 46. On the gear case 16 is a stub shaft 47 whereon is pivoted a stop lever 48 provided with a wedge shaped and arcuate end 49. The extent of movement of the head 31 and the proportions of the notch 46 and end 49 are such that, with the head at either extremity of its movement the lever 48 may be rotated to force the wedge end 49 into the notch 46 and thus cause the head 31 to move in one direction or the other to disengage the clutch from the gear with which it is engaged at the time. It is obvious that upon freeing the end 49 from the notch 46 the plunger will act to cause engagement of the clutch with one of its gears.

Mounted on the sleeve 18 is a gear 50 which is keyed to said sleeve to revolve therewith. This gear 50 meshes with a gear 51 formed on a vertical shaft 52 which is journaled in a vertical sleeve 53 mounted in the carriage 12. On the upper end of the shaft 52 is fixed a bevel gear 54 which meshes with a bevel gear 55 on the inner member 56 of a telescopic arbor, this member being in the form of a sleeve journaled

in the upper part of the carriage 12. The outer arbor member 57 has its inner end slidably mounted in the inner member 56, being keyed thereto to rotate therewith. This outer member is journaled in a head 58 which is slideable on the carriage. This outer member 57 has an inner collar 59 and an outer collar 60 between which the head 58 is engaged so that movement of the head accomplishes movement of the outer member 57 of the arbor. The extremity of the outer member 57 is provided with threads to receive a wheel clamping nut 61 by means of which a grinding wheel 62 may be clamped on the arbor to revolve therewith. The usual guard hood 63 is provided on the carriage to protect the operator in case of breakage of the wheel 62. By means of the gearing just described the rotation of the shaft 14 causes rotation of the wheel 62 and movement of the outer arbor member telescopically may be made without affecting the rotation of said wheel.

The feeding of the grinding wheel intermittently towards the knife is accomplished as follows. A main feed shaft 64 is journaled in the carriage above and parallel to the shaft 14. This shaft projects outwardly of the carriage through a boss 65 and on its outer end is provided with a ratchet wheel 66 which is keyed securely to the shaft. On the boss 65 is pivoted a ratchet lever having one arm 67 carrying a gravity operated pawl 68. The other arm 69 of this lever is provided with a sleeve end 70 wherethrough passes the shank of an adjusting screw 71 which is screwed into the carriage and is provided with a collar 72 on which the sleeve end 70 rests. Between the knurled head of the screw 71 and the sleeve end 70 is a coil compression spring 73 which serves to hold the sleeve end down on the collar while permitting it to be forcibly raised. In the wall of the bore 40 is formed a vertical slot 74 wherethrough projects a pin 75 which is carried by the plunger 41. This pin projects beneath the arm 69 so that each time the plunger is raised the pin 75 lifts the arm 69 and this, by the action of the pawl 68 rotates the wheel 66 through a certain arc. The length of this arc is determined by the adjustment of the screw 71 since the higher the collar 72 is located the more the pin 75 can rise before engaging the arm 69 and, since the vertical movement of the pin is always the same, the less will it move said arm 69. On the inner end of the shaft 64 is a bevel gear 76 which meshes with a bevel gear 77 carried on the sleeve 53. This gear 77 meshes in turn with a bevel gear 78 fixed on one end of a shaft 79 which is journaled in a boss 80 in the carriage a collar 81 preventing longitudinal movement of said shaft. This shaft 79 has a threaded end which extends through a

threaded boss 82 depending from the head. Thus the rotation of the shaft 64 effects rotation of the shaft 79 and feeds the head 58 toward the knife. The adjustment of the 5 screw 71 thus controls the extent of revolution of the shaft or screw 79 and consequently the extent to which the wheel 62 is advanced at each reversal of movement of the carriage. In order to provide for a 10 quick adjustment of the position of the wheel 62 the pawl 68 may be thrown back to disengage it from the ratchet wheel and the latter manually rotated by means of the handles 83.

15 In order to provide for manually traversing the carriage, a shaft 84 is journaled in the bed and extends from side to side thereof. On this shaft is fixed a hand wheel 85 and splined a bevel gear 86 which meshes 20 with a bevel gear 87 fixed on a stub shaft 88 which also carries a spur gear 89 meshing with a similar spur gear 90 keyed to the shaft 25. Also the lever 36 is fixed to its pivot, which latter consists of a rod 91 25 having a laterally extending handle 92. By means of this handle the clutch 22 may be shifted to central position and there locked by the lever 48 so that the shaft 84 may be manually rotated and thus rotate the shaft 30 25 and move the carriage.

At the rear of the bed are knife rail supporting bosses 93 wherein are mounted knife rail arms 94 each having a split sleeve 95 at its upper end to receive one of the end journals 96 of a knife rail or support 97. These journals 96 permit angular adjustment of the knife rail so that the bevel of a knife K supported on said rail may be varied at will, clamping bolts 98 serving to clamp the split sleeves on the journals and thus to hold the rail in its adjusted position.

40 A circulating pump 99 is located in the bottom of the bed 10 and is driven by a belt 100 from a pulley 101 on the shaft 14. From this pump extends a feed pipe 102 which delivers to a flexible hose 103 supported on a bracket 104 on the carriage and connected to a supply pipe 105 fixed on the hood 63 and provided with a cock 106 positioned to 45 deliver water to the grinding wheel. A pan 107 beneath the grinding wheel catches the water running off the wheel and from this pan a return pipe 108 leads back to a tank 109 with which the suction of the pump communicates. Thus a continuous circulation 55 of water is kept up.

50 In operation a knife is secured on the knife rail or support and the machine started, the grinding wheel being first manually adjusted nearly or quite in contact with the knife. The carriage will then reciprocate and at each end of its movement the motion will be automatically reversed and, at the same time, the grinding wheel will be advanced. Thus a series of light and uniform

cuts may be taken on the knife edge which will effectually sharpen the knife without burning the edge, the resultant edge being straight and true so that veneering cut by a knife sharpened in this manner will likewise be straight and true.

I claim:

1. In a grinder for veneer knives, means to support a knife, a grinding wheel, driving means for said wheel, traversing means to move said wheel longitudinally in front of said knife support, reversing means for reversing the action of the traversing means at each end of the longitudinal movement of the grinding wheel, and an automatic feed 80 arranged to advance the grinding wheel toward the knife support in a step by step movement said automatic feed being operated by the action of the reversing means.

2. In a grinder for veneer knives, means to support a knife, a grinding wheel, driving means for said wheel, traversing means to move said wheel longitudinally in front of said knife support, reversing means for reversing the action of the traversing means at each end of the longitudinal movement of the grinding wheel, and an automatic feed 90 arranged to advance the grinding wheel toward the knife support in a step by step movement, said automatic feed being 95 arranged to operate upon the arrival of the grinding wheel at one extremity of its longitudinal movement and being actuated by the reversing means.

3. In a veneer knife grinder, a bed, a knife support at the rear of said bed and extending transversely thereof, a carriage on the bed mounted for reciprocation transversely of said bed in front of the knife support, means including an automatic reversing device for reciprocating said carriage, a telescopic grinding wheel arbor carried by the bed and including a wheel supporting section projectable toward the knife support, driving means for said arbor, and an 100 automatic feed connected to the projectable section of the arbor and arranged to advance the same toward the knife support in a step by step movement.

4. In a veneer knife grinder, a bed, a knife support at the rear of said bed and extending transversely thereof, a carriage on the bed mounted for reciprocation transversely of said bed in front of the knife support, means including an automatic reversing device for reciprocating said carriage, a telescopic grinding wheel arbor carried by the bed and including a wheel supporting section projectable toward the knife support, driving means for said arbor, an automatic 115 feed connected to the projectable section of the arbor and arranged to advance the same toward the knife support in a step by step movement, said automatic feed being 120 arranged to operate upon the arrival of the 125 130

grinding wheel at one extremity of its longitudinal movement.

5. In a grinder for veneer knives having a bed and a carriage traversing said bed, traversing means for the carriage, including a shaft extending across the bed and through said carriage, a pair of confronting bevel gears slidably and revolvably mounted on the shaft within the carriage to move therewith, a clutch member splined on the shaft between the said gears and movable to engage the gears selectively, clutch moving means carried by the carriage and including a rod projecting laterally from the carriage and a lever pivoted intermediate its ends and having its upper end connected to said rod, spaced trip collars supported from the bed and engageable by the lower end of the lever to initiate movement of said lever, and thereby start shifting of the clutch, means to effect complete movement of said clutch, and feed means actuated by the movement of said lever.

6. In a grinder for veneer knives having a bed and a carriage traversing said bed, traversing means for the carriage including a shaft extending across the bed and through said carriage, a pair of confronting bevel gears slidably and revolvably mounted on the shaft within the carriage to move therewith, a clutch member splined on the shaft between the said gears and movable to engage the gears selectively, a clutch moving rod projecting from said carriage, a pin projecting laterally from the projecting end of said rod, a lever pivoted to said carriage and having a slot receiving said pin, spaced stops supported from the bed and engageable by said lever to move the latter, said lever having anticalinal cam surfaces, a spring pressed plunger bearing on respective cam surfaces in respective positions of the lever, the movement of said lever effecting lifting of said plunger, a telescopic grinding wheel arbor on said carriage, a feed screw connected to one section of the arbor to protrude and retract the same and including a ratchet wheel a pawl engaging the ratchet wheel; a lever carrying said pawl, a pin projecting from the plunger for lifting the last mentioned lever, and means for holding the last mentioned lever a selected distance above the lowermost position of the pin whereby to regulate the extent of movement of the lever.

the lever to force said lever to its extreme positions means for feeding the grinding wheel towards the work, and actuating means therefor mounted on the carriage and thrown into operative position by the movement of the plunger.

7. In a grinder for veneer knives having a bed and a carriage traversing said bed, traversing means for the carriage including a shaft extending across the bed and through said carriage, a pair of confronting bevel gears slidably and revolvably mounted on the shaft within the carriage to move therewith, a clutch member splined on the shaft between the said gears and movable to engage the gears selectively, a clutch moving rod projecting from said carriage, a pin projecting laterally from the projecting end of said rod, a lever pivoted to said carriage and having a slot receiving said pin, spaced stops supported from the bed and engageable by said lever to move the latter, said lever having anticalinal cam surfaces, a spring pressed plunger bearing on respective cam surfaces in respective positions of the lever, the movement of said lever effecting lifting of said plunger, a telescopic grinding wheel arbor on said carriage, a feed screw connected to one section of the arbor to protrude and retract the same and including a ratchet wheel a pawl engaging the ratchet wheel; a lever carrying said pawl, a pin projecting from the plunger for lifting the last mentioned lever, and means for holding the last mentioned lever a selected distance above the lowermost position of the pin whereby to regulate the extent of movement of the lever.

In testimony whereof I affix my signature.

WILLIAM H. COLLIER.
